UNITED STATES PATENT OFFICE.

ALFRED KOEHN, OF NEW YORK, N. Y.

ADJUSTABLE STANDARD FOR MUSIC-RACKS.

SPECIFICATION forming part of Letters Patent No. 398,408, dated February 26, 1889.

Application filed September 21, 1888. Serial No. 286,003. (No model.)

To all whom it may concern:

Be it known that I, ALFRED KOEHN, of the city, county, and State of New York, have invented certain new and useful Improvements 5 in the Construction of Adjustable Standards; and I do hereby declare that the following is a full and exact description thereof, reference being had to the accompanying drawings, and to the letters of reference marked thereon, 10 making a part of this specification, in which—

Figure 1 is a central vertical section of my improved extension-standard for music-racks, lamp-stands, and other purposes. Fig. 2 is a detail view, in like section, illustrating the 15 holding-catches when released; and Fig. 3 is a detail, partly in section, of the upper end of the standard, showing a modification thereof.

The object of my invention is to provide an 20 adjustable extensible standard which shall be simple in construction and permit of ready adjustment to different heights.

It consists in the combination, with an adjustable tube telescoping within a fixed upright tube secured to a suitable base, and with 25 a rod playing longitudinally within the adjustable tube and fitted with a spring to uphold it, of a pair of swinging catches, each pivoted at one end to the lower end of the adjustable tube and at the other to a link, itself 30 pivoted to the lower end of the rod. The catches thus form a double toggle-joint, which operates under the stress of the spring to cause the outer ends of the catches to engage automatically the inner surface of the lower 35 fixed tube, and thereby prevent the descent of the adjustable tube without interfering with its ascent. The catches are released by a depression of the rod within the tube effected by suitable pressure upon the upper end of 40 the rod.

In the accompanying drawings, A represents a tubular upright standard firmly fixed in a suitable base, B, and closed at its upper end by a cap, C.

D is an extension-tube passing centrally 45 through said cap C and secured at its lower end to a plunger, W, fitted to play freely within the standard.

E is a central rod extending longitudinally 50 within the extension-tube D, to project and play through the plunger W at its lower end and through a head, F, secured upon the up-

per end of the tube D. A spiral spring, G, fitted within the tube D, engages the rod E and operates automatically to lift it upward. 55

Catch-bars H H are pivoted at their inner ends to the lower face of the plunger W at diametrically-opposite points, one on each side of the projecting end of the rod E, and these catch-bars are severally coupled to the end of 60 the rod by means of pivoted links K K, so that the upward tension of the spring G upon the rod will operate to force the ends of the catch-bars outwardly against the inside face of the tubular standard A. The ends of the 65

catches thus brought into frictional contact with the standard are beveled to present a sharp angle for contact, so that the stress of the spring G will suffice to give them such a hold against the face of the standard as will 70

positively prevent the extension-tube from dropping therein, the hold of the catches becoming, by reason of their angle of inclination, more firm and sure in proportion as the weight upon the extension-tube is increased. 75 These catches H H are readily released from the standard A by pushing the rod D downward against the stress of its spring, as shown in Fig. 2.

The head F upon the upper end of the extension-tube D is transversely slotted at L, and the upper end of the catch-rod E terminates within said slot. The depression of the catch-rod to release the catches may be effected by simply pressing upon its upper end 85 with a finger inserted for the purpose in the transverse slot or opening L in the head, the end of the rod being fitted with a knob or button M, as shown in Fig. 3. Preferably, however, a lever, N, is pivoted at one end 90 within the slot L, as shown in Fig. 1, to extend transversely over the end of the catch-rod E and rest thereon, its outer free end being bent downward, as shown at P in Fig. 1. By pressing this bent end P inward with a 95 grasp of the hand the rod E will be forced downward and the catches H H released to permit the tube D to drop, and its downward movement will be automatically arrested so soon as the lever is relieved from pressure at 100

any point by the tension of the spring G operating, in the manner described, to throw out the catches.

The extension-tube D is free to be raised at

pleasure, since the catches, from their inclination, offer no resistance to its upward movement and operate automatically to prevent its fall only.

5 The adjustable standard is completed for use by fitting to the head F a music-rack, R, or a lamp-stand, or any other device requiring vertical adjustment.

I am aware that two opposite gripping-jaws 10 pivoted to the lower end of an adjustable tube moving longitudinally within a standard, and which are thrown outward into engagement with the standard by means of two underlying springs whose direct action determines the force of said engagement, have heretofore been combined with a sliding rod forked at its lower end to bear directly upon said gripping-jaws to release them; but my invention differs therefrom in that I couple 15 the lower end of the rod by means of links to the two jaws, and form thereby a toggle-joint by means whereof the engagement of the jaws is readily enforced by an upward movement of the rod produced automatically by means

of an encircling spring, or in other suitable 25 manner. I thus produce a more efficient and compact device at less cost, and which is not wholly dependent upon springs for its action.

I claim as my invention—

The combination, in an adjustable stand- 30 ard, as described, with a tubular upright se- cured to a supporting-base, an adjustable tube moving longitudinally within said stand- ard, and a movable catch-rod extending through said tube, of the two catch-bars hinged 35 to the lower end of the adjustable tube to swing outwardly into contact with the inner side of the inclosing-standard, and the links coupling the free end of each catch-bar with the lower end of the rod, substantially in the 40 manner and for the purpose herein set forth.

In testimony whereof I have signed my name to this specification in the presence of two sub- scribing witnesses.

ALFRED KOEHN.
